UNITED STATES PATENT OFFICE.

JOHANN GUSTAV BIERICH, OF MENKENHOF, NEAR LIEVENHOF, RUSSIA.

BOBBIN.

SPECIFICATION forming part of Letters Patent No. 773,185, dated October 25, 1904.

Application filed January 7, 1904. Serial No. 188,134. (No model.)

To all whom it may concern:

Be it known that I, JOHANN GUSTAV BIERICH, manufacturer, a subject of the Emperor of Russia, and a resident of Menkenhof, near 5 Lievenhof, Russia, have invented a certain new and useful Improvement in Spools, Bobbins, and Similar Hollow Articles; and I do hereby declare the following to be a full, clear, and exact description of the invention, such as 10 will enable others skilled in the art to which it appertains to make and use the same, reference being had to the accompanying drawings, and to letters of reference marked thereon, which form a part of this specification.

15 This invention relates to spools, bobbins, and like hollow articles made of composite wood and paper material.

20 The object of the invention is to provide a spool, bobbin, or the like of simple, strong, durable, light, and inexpensive construction.

25 In the accompanying drawings, Figure 1 is a view, partly in elevation and partly in section, of a spool or bobbin embodying the invention. Fig. 2 is a transverse section thereof 30 through the body in line A A, Fig. 1. Fig. 3 is a transverse section of one of the spool-heads in line B B, Fig. 1.

Like letters of reference refer to like parts in the several figures.

30 The spool or bobbin consists of a tubular or hollow cylindrical body *a* and end disks or heads *b*, which are secured to the opposite ends of the tubular body. The latter is made of composite material consisting of alternate 35 layers or thicknesses of thin pasteboard or paper *c* and wood-veneer *d*, which are superposed and cemented together and rolled or bent and secured in tubular form. This composite material of the body is pliable and 40 tough and not liable to break, thus enabling the manufacture of tubes or hollow cylinders of relatively small diameter, while the resulting tube or hollow cylinder is very strong and durable and a poor conductor of heat.

45 The end disks or heads *b* of the spool or bobbin consist of blocks composed exclusively

of thin layers or sheets of wood veneer superposed with their fibers crossing each other and cemented together. The composite material for both the tubular body and heads is subjected to pressure, then dried, and thereafter the parts are fashioned to the proper shape and cemented together, then turned to the desired final form and varnished or otherwise finished. The heads are preferably connected 50 to the body by reduced cylindrical parts, which are inserted and cemented in the ends of the tubular body, which they brace against collapsing.

The spool or bobbin constructed as described is very strong and durable and not liable to split or break, is much lighter than a similar article of the same strength made wholly from either wood or pasteboard, and is cheaper to manufacture. The composite tubular body of pasteboard and wood veneer requires very little thickness and correspondingly little weight to give it the great rigidity and durability necessary to enable it to withstand the heavy strains and pressure in all directions to which it is subjected in winding thread or wire thereon.

I claim as my invention—

1. A spool or bobbin having a tubular body consisting of alternate united layers of pasteboard and wood veneer, substantially as set forth.

2. A spool or bobbin comprising a tubular body consisting of alternate united layers of pasteboard and wood veneer, and heads secured to the opposite ends of said body and consisting of united wood veneers, substantially as set forth.

In testimony that I claim the foregoing as my invention I have signed my name in presence of the subscribing witnesses.

JOHANN GUSTAV BIERICH.
